HOLDER FOR LIPSTICKS AND THE LIKE

Cyril W. Mellette, Middlebury, Conn., assignor to
Chase Brass & Copper Co. Incorporated, Water-
bury, Conn., a corporation

Application May 30, 1945, Serial No. 596,660

1 Claim. (Cl. 206—56)

1

The present invention relates to improvements in holders for lipsticks and other materials which it may be desired to dispense, and relates more particularly to holders of the general character which include within the structure a carrier which is advanceable and retractable lengthwise of the same, to project and retire the contents of the holder out of and into an end of the structure.

For purposes of convenience of description, the holder of the present invention will be herein referred to as a lipstick-holder, though the same is available for dispensing other desired materials.

It may here be explained that one of the outstanding objections to ordinary lipstick-holders of the character referred to, resides in the fact that the lipstick may be caused to smear the interior of the cap, either by reason of the restoration of the cap to the holder prior to the retirement of the lipstick proper, or by reason of the advancement of the lipstick after the cap is in place.

One of the main objects of the present invention is to provide a superior holder for lipsticks and other materials, including an advanceable and retractable carrier and a cap, and so constructed and arranged as to effectively guard against the smearing of the lipstick against the inner surfaces of the cap.

Another object of the present invention is to provide a superior holder of the character referred to, which will effectively guard against the movement of its cap into its normal covering position until such time as the lipstick proper is retired into the holder.

A further object of the present invention is to provide a superior holder of the character referred to and having means to resist the advancement of the carrier after the cap is in place, to thereby avoid the likelihood of the lipstick being forced into engagement with the interior surfaces of the cap by the thoughtless manipulation of the parts.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a view in side elevation of an adjustable holder for lipsticks and the like, constructed in accordance with the present invention and with the cap fully in place thereon;

2

Fig. 2 is a similar view but with the cap removed;

Fig. 3 is an elevational view with the shell-member and stop-sleeve removed;

5 Fig. 4 is a similar view with the actuating sleeve removed;

Fig. 5 is a central-longitudinal sectional view taken on the line 5—5 of Fig. 1 but on a larger scale;

10 Fig. 6 is a transverse sectional view taken on the line 6—6 of Fig. 5;

Fig. 7 is a view similar to Fig. 6 but showing the cap removed and the carrier fully advanced;

15 Fig. 8 is a broken perspective view of the upper portion of the body-member detached; and

Fig. 9 is a broken perspective view of the outer end of the shell-member detached.

The adjustable holder which has been herein chosen for purposes of making clear one embodiment of the present invention, includes a cup-shaped carrier 10, a body-member 11 which is substantially of tubular form in its main portion, a longitudinally-split actuating-sleeve 12 and a tubular shell-member 13.

25 The parts above described may be made of any suitable material such, for instance, as sheet brass.

The carrier 10 above referred to is adapted to move axially within the body-member 11, while 30 the longitudinally-split actuating-sleeve surrounds the exterior of the said body and is frictionally coupled to the interior surface of the shell-member 13 by its inherent outward tension.

The body-member 11 is expanded at its inner 35 end to form a flange-like annular operating-head 14. Adjacent its outer end, the said body-member is formed with a substantially-annular outwardly-extending retaining-bead 15 which overhangs, so to speak, the outer edge of the actuating-sleeve 12 and serves to hold the same against axial outward displacement with respect to the body-member.

The body-member 11 is also formed with a longitudinal guide-slot 16 extending from a point 45 closely adjacent the operating-head 14 and intersecting the upper edge of the body-member. The upper-portion of one wall of the said guide-slot 16 is constructed and arranged to discharge the function of an actuator 17 for the hereinafter-described guard-finger 23, in a manner as will more fully hereinafter appear. The portion of the wall of the guide-slot 16 opposite the actuator 17 is cut away to provide a clearance-notch 18 which provides clearance for the guard-finger 55 referred to.

The actuating-sleeve 12 is preferably rolled up from a sheet of metal and is formed with a helically-inclined actuating-slot 19 which is adapted to receive the cylindrically-contoured head 20 of a radially-extending actuating-pin 21 mounted in the carrier 10 before referred to. The said head 20 of the actuating-pin 21 is located outside of the wall of the carrier 10 and rides in the longitudinal guide-slot 16 as well as in the helical actuating-slot 19 for purposes of causing axial movement of the said carrier in the body-member 11 when relative rotation takes place between the said body-member and the actuating-sleeve 12, in a manner as will hereinafter appear. In its upper edge the actuating-sleeve 12 is also formed with a clearance-notch 22 which is positioned to permit the free play of the latter described guard-finger 23.

As before noted the actuating-sleeve 12, due to its inherent tendency to expand laterally, is frictionally coupled to the interior surface of the shell-member 13 so that, for all functional purposes, the said actuating-sleeve constitutes a part of the said shell-member.

Adjacent its upper end the shell-member 13 is formed with an integral guard-finger 23 which is so tensioned as to tend to spring into an inward position as is especially well shown in Figs. 6 and 9.

Tightly mounted around the lower end of the shell-member 13 is a stop-sleeve 24 having its lower edge flush with the lower edge of the said shell-member and having its upper edge adapted to be engaged by the lower edge of an inverted cup-shaped cap 25 which has its interior dimensions such as to slip over the outer portion of the shell-member and to be lightly frictionally retained thereon.

To use the adjustable holder above described, the user may first remove the cap 25 and then by gripping the periphery of the shell-member 13 with the thumb and forefinger of one hand, the body-member 11 may be rotated by gripping the operating-head 14 thereof between the thumb and forefinger of the other hand.

The turning of the body-member in a clockwise direction (as viewed from the bottom) will cause the longitudinal guide-slot 16 in the body-member to bodily move the actuating-pin 21 to a similar extent. The bodily movement of the said actuating-pin will cause the same to be moved bodily outwardly by the appropriate wall of the helical actuating-slot 19 in the actuating-sleeve 12. The movement of the actuating pin 21 will cause a corresponding movement of the carrier 10 and thus ultimately project a body of lipstick 26 or other suitable material beyond the outer end of the shell-member 13.

Substantially as soon as the body-member 11 is rotated as above described, the actuator 17 thereof will engage with the guard-finger 23 of the shell-member 13 and flex the same outwardly so that the guard-finger projects beyond the periphery of the shell-member in a manner illustrated in Fig. 7. The continued turning movement of the body-member 11 until the lipstick 26 is fully projected beyond the open end of the shell-member 13, will cause the periphery of the upper portion of the body-member 11 to maintain the guard-finger 23 projected into its outward position, as shown in Fig. 7.

Now should the user absent-mindedly attempt to apply the cap 25 prior to having retired the carrier 10 and its contents, the guard-finger 23 will prevent this application.

The carrier 10 and the lipstick 26 carried thereby may be retired back into the positions in which they are shown in Fig. 5 by turning the body-member relative to the actuating-sleeve 12 and shell-member 13 in a reverse (counterclockwise) direction from that above described, whereupon the coincidental action of the longitudinal guide-slot 16 and the helical actuating-slot 19 will shift the said carrier and lipstick 26 inwardly. When the carrier 10 and the lipstick 26 are fully retired inwardly as described, the clearance-notch 18 in the upper portion of the body-member 11 will be again brought into registry with the free portion of the flexible guard-finger 23, whereupon the said guard-finger will by its own inherent tension spring inwardly into the position in which it is particularly well shown in Fig. 6, and therefore within the boundary described by the outer surface of the shell-member 13. The cap 25 may now be restored into the position in which it is shown in Figs. 1 and 5 without interference from the guard-finger 23.

When the cap 25 is in place, it will act to restrain the guard-finger 23 from being flexed outwardly, and hence should the user inadvertently attempt to turn the operating-head 14 without having first removed the cap 25, such action will be resisted. The resistance referred to will be afforded by the engagement of the actuator 17 of the body-member 11 with the guard-finger 23 which latter, under the conditions just described, is firmly held against outward flexure by the presence of the surrounding cap 25.

Thus by means of the construction and arrangement of parts such as shown in the accompanying drawings and above described, the application of the cap 25 or its equivalent to the remainder of the structure is guarded against until such time as the carrier 10 and the lipstick 26 have been substantially fully retired, to thereby avoid having the interior of the cap 25 smeared with the lipstick or other material 26 held in the carrier 10.

Furthermore, when the cap 25 is in place the inadvertent manipulation of the operating-head 14 is guarded against to again, under these circumstances, guard the cap from being smeared with the lipstick material.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claim are intended to be embraced therein.

I claim:

In a rotary lipstick-holder of the type having a shell-member, a body-member rotatable within the said shell-member, a lipstick-carrier movable lengthwise within the said body-member, advancing-and-retracting means to advance and retire the said carrier by a relative rotary movement between the said body-member and shell-member, and a removable closure-cap telescopically fitting over the exterior of the said shell-member; the improvement which includes: a flexible guard-member carried by the shell-member adjacent its outer end and movable laterally with respect to the said body-member and shell-member into and out of the path of the said telescoping closure-cap, the said flexible guard-member being spring-set to normally lie inwardly out of the path of movement of the said closure-cap, the said body-member being formed adjacent its outer end with

a clearance-opening receiving the said guard-member when the said carrier-member is in its retired position; and actuating-means adjacent the edge of the said clearance-opening and having camming engagement with the said guard-member to project the latter laterally outwardly into the path of the said closure-cap when the body- and shell-members are relatively turned in the direction serving to cause the said advancing-and-retracting means to advance the said carrier, to thereby hinder the inadvertent telescoping of the said cap over the said shell-member.

10 CYRIL W. MELLETTÉ.
